UNITED STATES PATENT OFFICE.

JOHN P. ODGERS, OF PHILADELPHIA, PENNSYLVANIA, ASSIGNOR TO THE
A. M. COLLINS MANUFACTURING COMPANY, OF SAME PLACE.

DESIGN FOR A PICTURE-MOUNT.

SPECIFICATION forming part of Design No. 28,711, dated May 24, 1898.

Application filed April 22, 1898. Serial No. 878,527. Term of patent 7 years.

To all whom it may concern:

Be it known that I, JOHN P. ODGERS, a citizen of the United States, residing in Philadelphia, Pennsylvania, have invented a new and original Design for a Picture-Mount, of which the following is a specification.

My design is fully shown in the accompanying drawing, which represents a face view of a mount embodying the design, the border being drawn on an exaggerated scale as compared with the dimensions of the card.

The design is of rectangular form and presents an inner panel or tablet 1, surrounded by a groove 2, crossed at the corners by diagonal ribs 3. Outside of this groove is a wide border, and outside of the latter is a narrow border. The wide border has narrow edge bands 6 and 7, between which are waved ribs 8, which swell and contract, and under the

effect of light form a zigzag pattern on border. This is the prominent feature of design. The narrow outer border consists of a zigzag rib 9, between which and the outer band 7 of the wide border are a series of dots 10, while outside of the zigzag rib 9 the border has a granular surface with leaf-shaped figures 11.

I claim—

The design for a picture-mount, substantially as described and as shown in the accompanying drawing.

In testimony whereof I have signed my name to this specification in the presence of two subscribing witnesses.

JOHN P. ODGERS.
